US0D1061259S

(12) **United States Design Patent** (10) **Patent No.:** **US D1,061,259 S**
(45) **Date of Patent:** **** Feb. 11, 2025**

(54) **BOTTLE**

- (71) Applicant: **Homecourt Inc.**, Santa Monica, CA (US)
- (72) Inventors: **Courtney Cox**, Malibu, CA (US); **Sarah Jahnke**, Dallas, TX (US); **Nick Axelrod-Welk**, Los Angeles, CA (US)
- (73) Assignee: **Homecourt Inc.**, Santa Monica, CA (US)

(**) Term: **15 Years**

(21) Appl. No.: **29/952,952**

(22) Filed: **Jul. 18, 2024**

Related U.S. Application Data

(63) Continuation of application No. 29/883,224, filed on Jan. 25, 2023, now Pat. No. Des. 1,043,358.

CLAIM

The ornamental design for a bottle, as shown and described.

DESCRIPTION

FIG. 1 is a front, upper, left perspective view of a bottle of our new design;

FIG. 2 is a rear, lower, right perspective view;

FIG. 3 is a left view thereof;

FIG. 4 is a right view thereof;

FIG. 5 is a front view thereof;

FIG. 6 is a rear view thereof;

FIG. 7 is a top view thereof; and,

FIG. 8 is a bottom view thereof.

Broken lines of equal length (e.g., dash-dash) represent unclaimed subject matter and form no part of the claimed design. Broken lines of unequal length (e.g., dash-dot) define bounds of the claimed subject matter and form no part of the claimed design.

1 Claim, 8 Drawing Sheets
